INVENTOR

Thomas A. Dickinson,
By, George, Jacobs, Burgess & Pardee,
his Atty.

UNITED STATES PATENT OFFICE.

THOMAS A. DICKINSON, OF YOUNGSTOWN, OHIO.

ANTITHEFT DEVICE FOR ELECTRIC-LAMP BULBS.

Application filed April 22, 1922. Serial No. 556,045.

To all whom it may concern:

Be it known that I, THOMAS A. DICKINSON, a subject of the King of Great Britain, and a resident of Youngstown, in the county 5 of Mahoning and State of Ohio, have invented a new and useful Improvement in Antitheft Devices for Electric-Lamp Bulbs, of which the following is a full, clear, and exact description.

10 My invention relates to means for preventing theft of electric light bulbs, and will be better understood by reading the following description taken in connection with the accompanying drawing forming a part 15 thereof and in which—

Figure 1 is a view showing a lamp bulb with my invention applied thereto and screwed into an ordinary socket, the socket being shown in section;

20 Figure 2 is a plan view of one element of the device;

Figure 3 is a plan view of another element of the device;

25 Figure 4 is a central section of the element of Figure 3;

Figure 5 is a plan view of another element,

Figure 6 is a section on line VI—VI of Figure 5; and

30 Figure 7 is a view of a portion of a bulb prepared for receiving the protective device.

In Figure 1 of the drawings is shown an ordinary lamp socket 1 which may be of any desired construction. A lamp bulb 2 of the ordinary construction is adapted to be 35 screwed into the socket 1. The socket shown comprises a metal portion 3 which is separated from the interiorly threaded socket 4 by insulation 5. One of the wires 6, connects with the socket 4, and the other wire 7, 40 connects with the central contact 8 of the socket. The contact 8 is insulated from the socket 4 by the insulating disk 9. The lamp shown is of the ordinary construction and is provided with a central contact 10 to which 45 is connected one end of the filament 11. The other end of the filament 11 is connected with the base 13, which is provided with threads in the ordinary manner and is adapted to be screwed into the socket 4. When 50 the lamp is screwed into the socket, the base is electrically connected with the socket 4 and the contact 10 engages the contact 8 so that a circuit is made from the supply lines 6 and 7 through the filament 11.

55 The parts so far described are of standard

construction and per se form no part of my invention, and may be varied at will.

My device comprises the parts shown in Figures 2 to 6, inclusive, in combination with the elements heretofore described. In applying my device to the ordinary lamp bulb, the edges of the central contact 10 are slightly raised by means of a knife or similar instrument, and the washer 14 is placed around the portion 15 of the base. The washer 14 takes the position shown in Figure 1. A washer 16 is then placed around the part 15 on the base and takes the position shown in Figure 1. The washer 16 is of insulating material, and the opening 70 therein is made to fit the part 15 of the base. The lock washer 17, shown in Figure 2, is then placed in the position shown in Figure 1, and acts to hold the washers 14 and 16 in place, the slot 18 being of sufficient size to 75 receive the stem of the contact 10 of the lamp base.

The washer 14 is preferably provided with two flat portions 19 for a purpose which will appear later. The diameter of the washer 80 14 is somewhat larger than that of the base of the lamp and may be made of any suitable material. The weight of the material from which the washer 14 is made depends somewhat upon the size of the lamp to which 85 it is to be applied.

When the lamp is screwed into the socket, the edges of the washer 14 will engage the socket and will be bent slightly downward, as shown in Figure 1. The shape of the base 90 and the flexibility of the washer 14 will permit the base with the washer thereon to be easily screwed into the socket, and the washers 16 and 17 will act to hold the washer 14 in place so as to avoid short-circuits. If it is attempted to unscrew the lamp from the socket, the edges of the washer 14 will jam in the threads of the socket and will tend to hold the base in the socket. If sufficient effort is applied to the lamp to unscrew the 95 base, the washer 14 will be tightly jammed in the threads of the socket and the central contact 10 will be pulled out of the base and the lamp rendered useless because the same cannot be again used until after another central contact has been applied to the base and suitable connections made to the leading-in wires. By reason of the fact that the removal of the base from the socket with this 105 device applied renders the lamp useless, un- 110

authorized persons will have no motive for removing the lamps from the sockets. The parts 14, 16 and 17 will remain in the socket after the base has been screwed out. These parts may be easily removed from the socket, preferably after the current has been turned off therefrom, by inserting a hook under one edge of the washer 14 and turning the same until the two flat sides 19 extend longitudinally of the socket. The diameter of the washer across the two sides 19 is smaller than that of the socket, as a result of which the parts will readily pass out of the socket.

My invention has many advantages, among which may be mentioned that it is simple, easily applied, is effective and may be re-used many times, is inexpensive, entirely safe, and may be applied to a standard lamp bulb without substantial alteration thereof.

I claim:

1. An anti-theft device for electric lamps, comprising a flexible member attached to the lamp base and overlying the end thereof, said member being adapted to jam in the threads of the socket upon attempted removal of the base from the socket, substantially as described.

2. An anti-theft device for electric lamps, comprising a flexible member attached to the base and adapted to assume a concave position as the base is screwed into the socket and to jam in the socket upon attempted removal of the base from the socket, substantially as described.

3. An anti-theft device for electric lamps, comprising a flexible member overlying the end of the lamp base and adapted to jam in the lamp socket upon attempted removal of the base therefrom, and insulating material overlying said flexible member and secured to said lamp base, substantially as described.

4. An anti-theft device for electric lamps, comprising a flexible disk attached to the lamp base and having a diameter greater than that of the lamp socket, said disk being adapted to jam in the socket upon attempted removal of the base from the socket, substantially as described.

5. An anti-theft device for electric lamps, comprising a flexible member, and means for removably securing said member to the center contact of a lamp base, said member having a diameter greater than the lamp socket and being adapted to jam in the socket upon attempted removal of the base from the socket, substantially as described.

6. An anti-theft device for electric lamps, consisting of a member attached to the central contact of the lamp and having a portion adapted to engage the socket and to be bent in a direction towards the filament when the base is screwed into the socket, substantially as described.

7. An anti-theft device for electric lamps,

consisting of a member attached to the central contact of the lamp and having a portion adapted to engage the socket and to be bent in a direction towards the filament when the base is screwed into the socket and to jam in the socket as the base is unscrewed from the socket, substantially as described.

8. The combination with a lamp base having a central contact on the end thereof, of means carried by said lamp base and adapted to interlock with means on the lamp socket upon attempted removal of the base therefrom, and means including insulating material interposed between said first-mentioned means and said central contact for securing said first-mentioned means to said lamp base, substantially as described.

9. The combination with a lamp base having a central contact on the end thereof, of a flexible washer of greater diameter than said lamp base overlying the end of the latter, and a washer of insulating material interposed between said flexible washer and said central contact, substantially as described.

10. The combination of a lamp base, a central contact thereon, a flexible washer on the end of said base and surrounding said central contact and of sufficient diameter to engage the socket when the base is placed in the socket, and a relatively rigid member engaging the other side of said flexible washer and of smaller diameter than the socket, said rigid member being attached to the base through said central contact, substantially as described.

11. The combination of a lamp base, a central contact thereon, a flexible washer on the end of said base and surrounding said central contact and of sufficient diameter to engage the socket when the base is placed in the socket, a relatively rigid member engaging the other side of said flexible washer and of smaller diameter than the socket, and means for attaching said rigid member to said central contact, substantially as described.

12. The combination with a lamp base having a central contact on the end thereof, of a flexible washer overlying the said end and attached to said contact, said washer being of such dimensions as to peripherally engage the walls of the socket and thereby be flexed to permit the base to be screwed into the socket and to jam in the socket upon attempted removal of the base therefrom and having diametrically opposite flattened sides to permit removal of the washer from the socket upon rotation of said washer so that such flattened sides extend longitudinally of the socket, substantially as described.

In testimony whereof I have hereunto set my hand.

THOMAS A. DICKINSON.
